ASH RECEIVER

Edward Gillisse and Cornelius Hendricks, Grand Rapids, Mich., assignors to Applied Arts Corporation, Grand Rapids, Mich., a corporation of Michigan

Application December 18, 1939, Serial No. 309,782

14 Claims. (Cl. 206—19.5)

This invention relates to ash receivers of the tilting type, which may be mounted at an opening in the vertical instrument panel of an automobile at the front of the driving compartment. Of course, the ash receiver may be mounted at other places not only in an automobile but upon any thin vertical support which has an opening for the reception of the receiver whereby when moved to closed position it is entirely concealed, but which may be tilted outwardly for the reception of ashes, cigarette and cigar stubs and other refuse.

It is an object and purpose of the present invention to provide an ash receiver which will be firmly yet yieldably held at both its inner closed and outer tilted position, which will not rattle or make other undesired noises because of vibration of the automobile body when it is being driven over the road, and which will not accidentally or inadvertently become detached from the instrument panel or other support on which it is mounted, but which can be detached therefrom when desired for dumping the contents of the receptacle as required from time to time.

The invention may be understood from the following description, taken in connection with the accompanying drawings, in which:

Fig. 1 is a central vertical section from front to rear of one embodiment or form of our invention.

Fig. 2 is a vertical section substantially on the plane of the broken line 2—2 of Fig. 1.

Fig. 3 is a side elevation and partial section showing the tiltable ash receiver at its outer position and stopped in such position.

Fig. 4 is a plan view of the tilting ash receiver.

Fig. 5 is an under plan view and partial horizontal section of the overhead cover plate and the open frame to which it is connected.

Fig. 6 is a view similar to Fig. 1, showing the invention embodied in a slightly different form of construction.

Fig. 7 is a horizontal section substantially on the plane of line 7—7 of Fig. 6, looking in a downward direction.

Fig. 8 is a section similar to Figs. 1 and 6, showing a further specific and different structural embodiment of the invention.

Fig. 9 is a partial vertical section and rear elevation, looking forward on the plane of the broken line 9—9 of Fig. 8, and

Fig. 10 is a vertical section similar to Figs. 1, 6 and 8 of a still further and more simplified embodiment of our invention.

Like reference characters refer to like parts in the different figures of the drawings.

The instrument board or panel 1, positioned in a substantially vertical plane, has an opening therethrough and at the upper edge of said opening a tongue 2 of metal integral with the instrument panel 1 is turned to the rear as shown. The opening is surrounded by an open frame which has upper and lower horizontal sides 3 and 4, with vertical side members integrally connecting them. From the upper edge of the lower member 4 inwardly and downwardly curved supporting shoes 5 are bent which extend through the opening and are bent downwardly back of the instrument panel 1. At the lower edge of the upper side 3 of the frame, the metal is formed into a longitudinal bead 6, which extends across the upper part of the opening; and back of the bead, preferably at a central point between the sides of the opening, a stop lug or tang 7 is pressed downwardly. The open frame at its outer portions is reinforced and given an ornamental character by the beads indicated at 8.

A cover plate 9 of sheet metal is secured at its front end by spot welding or other equivalent securing means to the rear side of the upper side 3 of the open frame described. Said cover plate is of a curved form and extends downwardly and rearwardly back of the panel 1. The plate is provided with downwardly pressed spaced apart ribs 10 for reinforcement. At its forward portion a tongue 11 is struck upwardly and extended forwardly to come directly underneath the rear portion of the part 2, and through the contacting parts 11 and 2 a bolt 12 is passed. Other bolts 13 are passed through the lower side 4 of the frame and through the instrument panel 1 back of it, so that the open frame with the connected cover plate 9 is securely connected in a rigid relation to the instrument panel.

The ash receiving receptacle is made of sheet metal and, as shown in Figs. 1 and 2, it has a body with a horizontal bottom 14, a vertical front 15, and a vertical back 16. The metal of the back 16 is continued in a forward and outwardly curved direction in a section 17, which terminates short of the front 15 and carries an open cup-shaped snuffer 18. Between the snuffer and the back 16, an upwardly projecting stop lug or tang 19 is struck from the section 17, as shown in Fig. 1.

The receptacle is completed by two sides 20 of sheet metal which are flanged inwardly around their edges as at 21 to overlap the adjacent bottom and vertical front and rear of the body to

which they are connected by spot welding to provide a receptacle having an open upper side except where the section 17 partially covers it. The flanges 21 at the upper edges of the sides 20 are formed each with two transverse depressions or recesses 22 and 23, the former at the front ends of said flanges and the latter at a point between the snuffer and the stop 19.

The vertical front 15 is covered by an ornamental cover plate 24, inwardly flanged at its edges for appearance, strength and reinforcement. A handle 25 at the front side of the cover plate 24 is connected to the receptacle by means of a screw 26, which passing through the front side 15 of the receptacle and threading into said handle 25, serves also to secure the ornamental cover plate 24 in place. Such cover plate extends below the bottom of the receptacle and at its flanged lower edge a vertical tongue 27 is provided and extends upwardly toward, but terminates a short distance below the bottom 14. A spring member 28 of the form shown lies at the under side of the bottom 14 and is connected at its rear portion with said bottom 14 by spot-welding or other equivalent connection. The spring member 28 is curved downwardly and forwardly and is then curved upwardly and forwardly substantially in the arc of a circle as at 29, its free forward end reaching nearly to the rear side of the cover plate 24 and extending over the upper end of the tongue 27. The forward curved section 29 of the spring is shaped at its under side to conform to the convex curved upper surface of the supporting shoes 5.

This ash receiving receptacle is inserted through the opening in the instrument panel and through the open frame which surrounds such opening in the panel, with the upwardly and forwardly curved portion 29 of the spring 28 riding upon the shoes 5. When thus mounted upon the panel the spring 28 has a tendency to move the ash receptacle in an upward direction and thereupon force the section 17 at its side edge portions, where they come underneath the upper flanges 21, against the ribs provided in making the depressions at 23. In such position the stop 19 is slightly below the under side of the cover plate 9. The ash receiving receptacle may be tilted forward as shown in Fig. 3, and it will tilt until the rear stop 19 comes against the forward stop 7. The extent of movement of the front free end 29 of the spring member 28 toward the bottom 14, is limited as appears in Figs. 1 and 3, and a mere grasping of the sides of the ash receptacle with a downward pressure thereon which would bring the part 29 against the bottom 14 of the ash receptacle is not sufficient to depress the stop 19 below the stop 7 so as to disengage therefrom. Therefore, there will be no inadvertent or accidental disengagement of the ash receptacle from its panel mounting. In order to secure such disengagement, pressure is applied to the free end of the section 17 or against the upper end of the snuffer 18, to spring the section 17 in a downward direction a sufficient distance that the stop 19 will pass under and clear the front stop 7. When this is done the receptacle may be tilted still farther forward and removed from the instrument panel mounting therefor, and any ashes or other refuse therein dumped. The receptacle is then replaced by reversing the process, that is, inserting the rear portion of the receptacle into the opening, bringing the curved section 29 of the spring 28 against the shoes 5, and pushing the re-

ceptacle back to its closed vertical position as in Fig. 1. Because of the cooperating inclinations of the stops 19 and 7, said stop 19 will ride freely underneath the stop 7 upon replacement of the receptacle.

It will be apparent that in the closed position of the receptacle, the rib 6 enters the recesses at 22 at the front ends of the upper flanges 21, and that when the receptacle is tilted outwardly the spring at 28 yields sufficiently for the rib to disengage from said recesses. The upper flanges 21 will ride against the under side of the rib until the recesses at 23 are brought to said rib 6, whereupon the rib will enter the recesses at 23 as shown in Fig. 3. The construction described is of a practical and simple design, readily and easily manufactured at low cost. The movement of the spring 28 away from the bottom 14 is limited by the tongue 27. Therefore, the spring 28 is under tension as it is bent toward the bottom 14 and under tension even when the receptacle is free of its mounting. The spring forces the receptacle upwardly to cause the flanges at 21 to bear with some pressure against the ribs 6 during the inward and outward movements of the tilting receptacle, and insures that at both its open and closed position such receptacle will be yieldingly held against accidental or aimless movement by insuring that the rib 6 will be seated in the recesses 22 or 23.

In Fig. 6 the open frame is eliminated, and at the upper and side edges of the opening in the panel 4 the metal of the panel is bent to form shoulders 30, while at the upper edge it is continued and pressed downwardly to provide a front stop 31. The cover plate 32 curved downwardly and rearwardly is secured to the panel by welding or other appropriate means and is formed with front and rear upwardly pressed recess portions 33.

The receptacle has a rear side 34, a bottom 35 which, a distance back of the front of the receptacle is turned upwardly in a short vertical section 36 and then curved and extended forwardly in a short horizontal section 37, then continued vertically to make the front side 38. At the upper edge of the front side 38 the metal from which the body of the receptacle is made is turned backwardly and curved substantially to conform to the curvature of the cover plate 32. It extends over the open upper side in a section 39 from the upper edge of the front to and over the upper edge of the back 34, as shown in Fig. 6. An opening is made in said section 39 for the passage of ashes and other refuse into the receptacle. The sides 20 and the flanges 21 to connect with the bottom and front and rear by spot-welding are the same as in the previously described structure. The snuffer 18 is located on and carried by the section 39 back of the opening therein, and a stop 19a is struck upwardly from the section 39 back of the snuffer.

At the rear side of the receptacle rollers 40 are mounted on vertical brackets 41 which are welded to said rear side 34. The rollers are adapted to ride against the cover plate 32 and seat in the recesses 33 when at closed or at an outer tilted position at which the stop 19a engages the stop 31. An ornamental front plate 42, rearwardly flanged at its edges at 43, is connected to the front 38 and extends a distance below the bottom 35 of the receptacle and may be sprung away therefrom a short distance. Between the plate 42 and the vertical section 36 there is a vertical

slot or recess open at its lower end. A spring member 44 is spot-welded or otherwise equivalently connected at its rear portion to the back of the bottom 35, curved downwardly and forwardly as shown and is then extended upwardly in a section 45 which passes in front of the part 36 and terminates in a curved hook or socket 46. A rod 47 is permanently mounted on ears 49, extending inwardly from the metal of the panel 1 at the sides of the opening therethrough and is to be received in the socket 46. At the lower side of the opening is an upwardly and inwardly curved air shield 50 of sheet metal.

In this structure the receptacle is mounted by the engagement of the hook or socket 46 over the rod 47, which lies between the flanged edges 43 of the cover plate and the hooked upper portion 46 of the section 45 of spring 44. The distance between the lower part of the socket 46 and the flanged edges of the front cover plate forms an entrance opening to the socket which is of less diameter than the diameter of the pivot pin or rod 47, with the sides of the entrance opening or recess formed by the spring 45 on one side and the front cover plate on the other side, one or both being yieldable. When the receptacle is put in place it is inserted so as to receive the rod at the lower portion of the passage or entrance opening between said edges of the flange 43 and the part 45, and the receptacle is forced downwardly with a bending of the spring section 45 to the rear until the hook or socket at 46 is reached, so that there is required some force to connect the receptacle in place with a snapping of the rod into position in the curved hook 46. The distance between the upper side of the hook and the lower side of the part 37 of the receptacle thereabove is limited so that any downward pressure upon the receptacle cannot carry it in a downward direction far enough to bring the stop 19a below the lower point of the stop 31. The spring 44 has a tendency to lift the receptacle and thus press the rollers 40 into contact with the cover plate 32, and causes the rollers to seat in the recesses 33 when they come thereto. No handle is required to operate this receptacle to tilt it outwardly as it can be operated by an inward push of the lower depending portion of the front plate 42. To disengage the receptacle completely for removal, a pressure is made upon the plate 39 or the upper end of the snuffer connected thereto to depress the stop 19a below the stop 31. It is of course to be understood, and as will appear hereinafter, that the rod 47 extending between the ears 49 may be replaced by two studs, one attached to each of the ears 49, the studs extending toward each other.

In Fig. 8 the structure bears many similarities to that shown in Fig. 6. The back 34 is not integral with the bottom 35 but is a separate piece flanged at its bottom edge to embrace and be welded to the bottom 35. The section 36 is closer to the ornamental front connected to the receptacle. The rollers 40 are carried by ears 51 integral with the back 34 and ride against the under sides of reinforcing ribs 10a which terminate at both ends short of the ends of the cover plate 32a in which they are formed, so that at front and rear positions the rollers pass beyond the ends of the ribs. The stop 31a is a pin rather than a downwardly struck tang from the cover plate 32a. The rear end of the upper member 39 is turned downwardly back of the rear side 34 and a tongue 52 is struck from the

back 34 to pass through an opening 53 in the overhead section 39, limiting the upward and downward bending movement of the part 39.

The front ornamental plate 42a is similar to the plate 42 in the previously described structure but is yieldably connected to the receptacle by means of pins 42b which extend therefrom, the upper one through the front 38 of the receptacle, and the lower one through the downwardly extending leg of an angle shaped bracket 54, the horizontal leg of which is spot-welded to the under side of the bottom 35, there being attaching washers 55 placed over the pins 42b to provide a permanent connection of the front ornamental plate. The rod 47 in Fig. 6, carried by the ears 49, is replaced by two studs 47a, with which the upper hooked ends 46 at the upper ends of arms 45 turned from the springs 44 engage, similar to the structure in Fig. 6.

In this case the socket which receives the pivot pins may be the same hooked portion 46 on the spring 45, or the socket may be formed in the portions 36 and 37a of the front of the receptacle and omit the spring, or it may be formed partly in the receptacle and partly in the front cover plate flanges. In any case the entrance opening to the socket will be the distance between the lower edge of the socket and the normal position of the front cover plate flanges, and will be less than the diameter of the pivot pins, so that, upon installation the lower part of the front plate must be sprung outwardly to permit the passage of the studs 47a between the flanged edges of the plate and the bottom of the socket. This springing away and yielding is permitted by an outward yield or bend of the vertical arm of the bracket 54. The snapping of the studs into place and their retention is effected the same as before. The rollers 40 are pressed upwardly against the under side of the cover plate 32 by the springs 44 in the same manner.

In Fig. 10 a simplification and economy in structure is effected. The rollers 40 are eliminated, the overhead section 39 does not carry any snuffer, and the front stop is provided by the edge of the flange at 31b, said flange being integral with the instrument panel 1. The cover plate 32b, similar to the plate 32a, is a plain plate without ribs or depressions and the stop 19b struck upwardly from the member 39 rides frictionally against the under side thereof and comes to the edge of the flange 31b when the receptacle is tilted outwardly to a predetermined position. The ornamental front plate 56 has a handle at its upper portion 57 connected by a screw 58 which passes through the front 38 of the receptacle, the front covering 56 and into said handle so that the lower depending portion of the front plate 56 has a capacity of being sprung slightly outward to permit the snapping on engagement with the studs 47. The rear sides of the hooks 46 in this case bear snugly against the front of the section 36, the same as in Fig. 8, requiring that the lower part of the ornamental front member 56 be sprung slightly outward when the receptacle is installed. In this case likewise a downward movement of the receptacle through inadvertence or accident is limited so that in no case will the upper edge of the stop 19b be brought below the front stop 31b unless manually depressed.

With the constructions described, the ash receiving receptacles are very economically produced, are certain in their operation, and are not liable to disengagement from the panel on

which they are mounted until such disengagement is purposely done.

The invention is defined in the appended claims and is to be considered comprehensive of all forms of structure coming within their scope.

We claim:

1. In an ash receiver structure, a vertical support having a receptacle receiving opening therein, means across the opening below the center thereof on which a receptacle may be mounted for tilting movement, a receptacle having an opening at its upper side, a spring member attached to the bottom of the receptacle adjacent the rear part thereof and extending forwardly and bearing upon said mounting means at its forward free end portion, a stop located adjacent the upper end of said opening, a second and downwardly movable stop carried at the upper part of and adjacent the rear of said receptacle, and a cover plate connected with the support and extending rearwardly therefrom underneath which the receptacle is adapted to pass, the distance between the forward free end of said spring member and the bottom of the receptacle when it is mounted upon the mounting means being less than the distance that the second mentioned stop normally projects above the lower end of the first stop, as and for the purposes specified.

2. In an ash receiving construction, a vertical panel of flat metal having a receptacle receiving opening therethrough, a mounting means for the receptacle located horizontally between opposite vertical sides of the opening below the center thereof, said mounting means having a curved bearing surface, a receptacle having an opening in its upper side adapted to be inserted through said opening in the panel, a spring member attached at its rear end to the under side of the bottom of the receptacle adjacent the rear part thereof and extending downwardly and forwardly therefrom for a distance, and terminating at its front end in a curved section adapted to engage with the curved surface of the mounting means, a cover plate attached to the panel adjacent the upper end of said opening underneath which the receptacle is adapted to be located when moved to inner position, said spring normally tending to elevate the receptacle to cause it to bear at its upper portions against the under side of said cover plate, cooperating stops, one fixed at a point adjacent the upper end of said opening and the other at the upper part and at a rear portion of said receptacle, for normally limiting the outward movement of said receptacle, yielding means carrying the stop on the receptacle whereby it may be depressed below the first stop, the free forward end of the spring on the bottom of the receptacle being spaced normally a distance from the adjacent portion of the receptacle when mounted on said mounting means less than the amount that said stop carried by the receptacle must be depressed in order to pass by the fixed stop.

3. In a construction of the class described, a substantially vertical panel having an opening for the entrance of an ash receiving receptacle, a horizontal means for mounting the receptacle at a point below the center of said opening, a receptacle having a closed front, back, sides and bottom, and a top having an opening therein for entrance of refuse into said receptacle, a spring member connected to the under side of the bottom of said receptacle at the rear portion thereof and extending forwardly and downwardly from its point of connection for a distance, and then

bent in an upward direction and terminating adjacent the front of said receptacle, at its upper end being shaped to conform to said mounting means, cooperating stops, one in fixed position adjacent the upper end of said opening and the other carried at the upper part of and at a rear portion of said receptacle for normally limiting the outward extent of movement of the receptacle, said stop carried by the receptacle being manually depressible to clear the fixed stop, whereby said receptacle may be moved outwardly farther to disconnect from said panel, said spring member preventing bodily downward movement of said receptacle a sufficient distance for the respective stops to clear each other to thereby prevent accidental or inadvertent disconnection of the receptacle from said panel.

4. An ash receiver structure comprising a substantially vertical panel having an opening therethrough into which an ash carrying receptacle may be passed, a rearwardly and downwardly curved shoe at the lower part of said opening in fixed relation to said panel, a cover plate extending rearwardly from said panel in fixed relation thereto having its forward end at the upper end of said opening, an ash receiving receptacle having an opening in its upper side adapted to be passed through said opening, a spring member of flat material permanently secured at its rear portion to the under side of and at the rear of the bottom of the receptacle, said member curving downwardly and forwardly from its point of connection for a distance and then curving upwardly and forwardly in a front section adapted to fit against said curved shoe, said spring being tensioned when engaged against said curved shoe and tending to elevate said receptacle to cause it to bear at its upper end portion against said cover plate, a fixed stop at the upper end of the opening, a movable cooperating stop carried by said receptacle at its upper part and toward the rear thereof normally engaging the fixed stop when the receptacle is tilted outwardly, manually operable yielding means carrying the stop on said receptacle whereby it may be depressed below the fixed stop, the free end of the spring which engages said shoe being spaced a distance from the bottom of the receptacle when it is installed in said opening in the panel less than the distance that the manually operable stop normally projects above the lower end of the fixed stop.

5. In an ash receiving construction, a vertical panel having a receptacle receiving opening therein, a pivot means carried by said panel having a horizontal axis located adjacent the lower portion of said opening, a cover plate carried by said panel at the upper end of said opening and extending rearwardly and curved downwardly therefrom, an ash receiving receptacle having an opening at its upper side for passage of refuse thereto, a flat spring member attached at its rear portion to the under side of and rear part of the bottom of the receptacle, said spring member being curved downwardly and forwardly and thence bent upwardly and terminating in a part to engage said pivot means, said receptacle at its front lower portion being rearwardly recessed and the free end of the spring extending upwardly into said recess, and a front plate attached to the front of said receptacle and extending below the bottom thereof, said receptacle being applied to the pivot means by forcing over the pivot means which traverses a space of less width than the diameter of the pivot means between

the front plate and the front end of the spring, whereby the spring is sprung rearwardly to permit the passage of the pivot means, thereby normally holding the receptacle against disengagement from said pivot means, as specified.

6. In an ash receiving construction, a vertical panel of flat metal having a receptacle receiving opening therethrough, a pivot mounting means for a receptacle having its pivotal axis extending horizontally across said opening at a lower portion thereof, a receptacle having a bottom, a vertical front, a back and sides and having an opening at its upper end for reception of refuse, said front at the lower portion thereof being extended rearwardly for a short distance and then downwardly to connect with said bottom, a front plate attached over the front of said receptacle and extending below the bottom thereof, and a flat spring member secured at its rear portion to the bottom at the rear part thereof and thence curving downwardly and forwardly and having a front end portion bent therefrom extending upwardly between the front plate and the lower part of the front of said receptacle, the spring terminating in a curved hook adapted to engage and fit said pivot means, the space between said upwardly extending portion of the spring and the front cover plate being less than the diameter of the pivot means, whereby in connecting the receptacle to the pivot means said spring and front cover plate are sprung apart to permit the passage of said pivot means, thereby yieldingly holding said receptacle in connection with the pivot means against accidental or inadvertent disconnection therefrom.

7. A construction containing the elements in combination defined in claim 6, combined with a cover plate carried by said panel and extending rearwardly and downwardly therefrom from adjacent the upper end of said opening through the panel, and means on the receptacle bearing against the cover plate and normally pressed thereagainst by said spring.

8. A construction containing the elements in combination defined in claim 6, combined with a cover plate attached to said panel and extending rearwardly and downwardly therefrom from adjacent the upper end of said opening, said cover plate having two spaced apart upwardly pressed recesses therein, and a roller carried at the upper part and on the back of said receptacle, engaging the lower side of said cover plate and being pressed thereagainst and into said recesses by said spring, said roller seating in the rear recess when the receptacle is at its closed position and the front recess when at a forward position, and cooperating stops, one fixed with relation to the forward portion of the cover plate and the other carried by the receptacle engaging each other when the receptacle is tilted outwardly to a predetermined position, in which said roller enters the forward recess in the cover plate.

9. An ash receiver comprising, a mounting plate having an opening, a pivot pin adjacent said opening, a receptacle, and means for pivotally mounting said receptacle on said pivot pin for movement in said opening consisting of a socket to receive said pivot pin, said socket having a yieldable side and the entrance opening to said socket being of less width than the diameter of the pivot pin.

10. The elements in combination defined in claim 9 in which the front of the receptacle extends to a location abreast of said pivot pin and said yieldable side consists of a spring element mounted on said receptacle.

15 11. An ash receiver comprising a panel structure consisting of a supporting panel having an opening and a cover plate attached to the panel, a pivot pin adjacent said opening, a receptacle beneath said cover plate and movable in said opening, a yieldable socket on said receptacle embracing said pivot pin, said socket having an entrance opening of less width than the diameter of said pivot pin and means for moving at least a portion of said socket yieldably in a direction to thrust a part of said receptacle into engagement with said cover plate.

20 12. The elements in combination defined in claim 11, in which the receptacle has a front plate which forms a part of said socket, another part of said socket being formed by a spring member yieldable to permit entrance of said pivot pin into said socket and also acting to thrust a part of said receptacle into engagement with said cover plate.

25 13. An ash receiver comprising a mounting panel having an opening, a pivot pin adjacent said opening, a receptacle movable in said opening, said receptacle having a front member and a socket formed on said receptacle to receive said pivot pin, said socket having an entrance opening of less width than the diameter of said pivot pin and said socket being formed in part by a portion of said front member, said front member being yieldable relative to another part of said receptacle.

30 14. An ash receiver comprising, a panel having an opening therein, a pivot pin adjacent said opening, a receptacle movable in said opening, a front plate on said receptacle movable therewith, a socket formed between said plate and the front of said receptacle to receive said pivot pin, the width of the entrance opening to said socket being less than the diameter of said pivot pin, and the connection between the front plate and said receptacle being yieldable, whereby, upon insertion of the receptacle into the opening, the front plate will yield to permit reception of the pivot pin into said socket, permitting the pivot pin to snap into place.
